TAPE GUIDING ATTACHMENT FOR SEWING MACHINES

Filed Jan. 23, 1929

UNITED STATES PATENT OFFICE

HENRY J. REITER, OF PHILADELPHIA, PENNSYLVANIA, ASSIGNOR TO THE DE LONG HOOK AND EYE COMPANY, OF PHILADELPHIA, PENNSYLVANIA, A CORPORATION OF PENNSYLVANIA

TAPE GUIDING ATTACHMENT FOR SEWING MACHINES

Application filed January 28, 1929. Serial No. 334,375.

My invention relates to attachments which are adapted for employment upon sewing machines in operative relation to the sewing mechanism thereof for guiding either an eye tape or a hook tape to the sewing mechanism.

The invention has especial relation to attachments for guiding eye tape of the character in which a cover strip is provided for covering and concealing the rear portions of the fasteners and between which and the main body of the tape an edge portion of a garment or the like is secured. The cover strip is adapted to cover and conceal all portions of the eyes except the forward operative loop end portions thereof.

To facilitate the insertion of the edge of the garment between the cover strip and the main body portion of the tape the said cover strip is first secured along one edge to the main body portion of the tape by a line of thread stitching which extends crosswise of the eyes, the unfastened remaining portion of the cover strip being bent or turned over the said line of stitching and over the front ends of the eyes. The edge portion of the garment to which the tape is to be secured is placed over the rear end portions of the eyes and adjoining portions of the main body of the tape after which the cover strip is folded down over and onto the edge portion of the garment and secured to the latter and to the adjoining portion of the main body of the tape by a line of stitching formed therein.

The general object of the invention is to provide an attachment having means of novel construction for turning the said cover strip from open position into closed position overlying the edge portion of a garment so that the tape and garment are assembled in advance of the sewing mechanism of the sewing machine whereby the securing of the tape to the garment is facilitated.

It also is an object of the invention to provide a novel tape guiding attachment which not only is of extremely simple construction but which is highly efficient for the purpose above indicated.

Another object of the invention is to provide the attachment with means to facilitate

the location of an end of the edge portion of the garment to which the tape is being secured in proper position relative to the length of the tape and to the fasteners, whether eyes or hooks, carried thereby.

Without attempting to set forth the many and various other objects of the invention I shall now proceed with a detailed description thereof wherein will be pointed out other and additional objects or else such other and additional objects will become apparent from the said description.

In order that the invention may be understood readily and its practical advantages fully appreciated reference should be had to the accompanying drawings wherein I have illustrated one mechanical embodiment thereof in the form which at present is preferred by me. It will be understood that the invention is susceptible of embodiment in other forms of construction than that shown, and that changes in the details of construction may be made within the scope of the claims without departing from the invention or the principle thereof.

In the drawings:

Fig. 1 is a view in top plan of an attachment embodying the invention and of a fragmentary portion of a sewing machine upon the table of which the said attachment is mounted;

Fig. 2 is a longitudinal sectional view of the said attachment mounted upon the sewing machine table, as shown in Fig. 1, and showing a portion of the said table in transverse section and portions of the sewing mechanism in elevation;

Fig. 3 is a view in transverse section showing one form of tape which is adapted to be guided by the said attachment;

Fig. 4 is a view in transverse section taken on the line 4—4 of Fig. 1;

Fig. 5 is a transverse sectional view taken on the line 5—5 of Fig. 1;

Fig. 6 is a sectional view taken on the line 6—6 of Fig. 1, a portion of the said attachment being shown in transverse section;

Fig. 7 is a view in elevation of a portion of one end of the attachment looking from the right toward the left in Fig. 1; and

Fig. 8 is a transverse sectional view of a portion of the attachment taken on the line 8-8 of Fig. 1.

In the drawings I have shown a fragmentary portion of a sewing machine table 1 upon which the attachment is mounted. The sewing mechanism is of usual construction and comprises two needles, one of which is shown at 2, a needle supporting bar 3, a presser foot 4 and its supporting bar 5, a feed plate 6 having an opening 7 therethrough into which the serrated upper face portion of a feed dog 8 is adapted to be projected, which feed dog is supported upon a supporting arm 15 or the like 9. For feeding the work the feed dog may be given a four-motion movement by known means, as usual. The feed dog is provided with a couple of openings 10 into which the needles 2 enter in the sewing operation.

Although, as previously indicated, the attachment as illustrated is adapted especially for the guiding of the eye tape of hook and eye tape garment fastening means, it is to be understood that the principle of the invention is applicable to attachments for guiding the hook tape of hook and eye tape garment fastening means.

The attachment comprises a base plate having what may be regarded as a bottom portion 15, the latter in turn having at its opposite edges portions 15^a and 15^b which are turned over and inwardly of the said bottom portion and are spaced in parallel relation thereto as shown in the drawing. A plate 16 is located directly underneath the inwardly turned portion 15^a and its inner edge portion projects a considerable distance inwardly of the inner edge of the said portion 15^a. A spacing plate or bar 18 is located between the outer edge portion of the plate 16 and the outer part of the bottom portion 15 of the base plate. The plate 18 is relatively narrow as compared with the plate 16 and is of a thickness to support the inner portion of the plate 16 in the desired spaced relation to the bottom portion 15 of the base plate. Mounted above the inwardly turned portion 15^a is a plate 17 which plate is spaced from the portion 15^a by means of an interposed plate 21. The combined thickness of the plate 21 and of the inwardly turned portion 15^a is such as to provide the required space between the inner edge portion of the plate 17, which projects beyond the inner edges of the portions 15^a and 21, and the corresponding portion of the plate 16. The several plates 15, 15^a, 16, 17, 18 and 21 may be secured together by soldering, welding, brazing or in any other way which may be known.

The rear end, that is, the left hand end having reference to Fig. 1 of the drawings, of the plate 17 terminates at 22 as indicated in Fig. 1.

The inner edge of the said plate 17 is provided with an inwardly and upwardly extending flange portion 25. The angle which the said flange portion makes with the plane of the plate 17 gradually decreases from the front end to the rear end thereof. At its front end the angle of the said flange portion 25 to the plate 17 may be approximately 45°. The said angle gradually decreases toward the rear end until finally at its rear end the angle which it makes with the said plate 17 is small, as is indicated in Fig. 5 of the drawings. It will be understood that the angular relation of the flange 25 to the plate 17 may be varied through practical limits without departing from the invention.

The purpose of the flange 25 is to engage and turn the cover strip 26 from the open position shown in Fig. 3 of the drawings over into very nearly closed position, as indicated in Fig. 5. The said cover strip is shown in different partially closed positions in Figs. 4 and 5. The cover strip 26 is turned into completely closed position by means of a short section of plate 25^a which although of greater thickness than the plate 17 constitutes in effect an extension thereof. The plate 17 preferably consists of German silver, whereas the plate 25^a preferably consists of brass because the latter offers greater resistance to the wearing action of the presser foot which in its operation may contact with the inner edge thereof than would the softer metal of the plate 17. It will be understood, however, that these plates may consist of any other suitable metal. The plate 25^a is mounted upon and over the plate 21 and may be secured thereto in any suitable manner as by soldering, welding, brazing and the like. The inner edge portion of the plate 25^a projects beyond the inner edges of the plate 21 and of the portion 15^a and is spaced in substantially parallel relation to the inner edge portion of the plate 16, as is clearly shown in Fig. 6 of the drawings. Preferably the under side of the inner edge portion of the plate 25^a projects slightly downwardly as indicated in Fig. 6.

The forward or front end of the flange 25 is cut or beveled off as shown at 27 in Fig. 1 for a purpose which hereinafter will be more fully explained. The inner edge portion of the forward or front end of the plate 16 also is cut away or beveled as shown at 28.

A plate 30 is mounted upon the outer edge portion of the bottom part 15 of the base plate in opposed relation, transversely of the attachment, to the tape guiding and supporting plate 16 previously referred to. The said plate 30 is supported in spaced relation to the bottom part 15 of the base plate by means of a plate 31 which is located between the outer edge portion of the plate 30 and the bottom part 15 of the base plate. The thickness of the plate 31 is sufficient to support the plate 30 in substantially the same plane as the plate 16.

The said plate 30 is held between the plate 31 and the inwardly turned portion 15^b previously referred to. The inner edges of the plates 16 and 30 are in opposed spaced relation to each other and to the bottom part 15 of the base plate as shown. The inwardly turned portion 15^b, which overlies and is in contact with the outer edge portion of the plate 30, and the plates 30 and 31 and the bottom part 15 of the base plate are secured together by soldering, welding, brazing or otherwise, as may be preferred.

In the employment or use of the device the opposite edge portions of the main or body portion of the tape pass through the said attachment underneath the inner edges of the plates 16 and 30. The front operative end portions 36 of the fasteners overlie the inner edge portion of the plate 16; that is, the inner edge of the plate 16 projects between the main or body part of the tape and the front operative end portions 36 of the fasteners. The said edge portion of the plate 16 constitutes a support and guide for the tape. The beveling or inclining of the inner edge portion of the front end of the plate 16 facilitates its entry between the front operative end portions 36 of the fasteners and the adjoining portion of the body part 35 of the tape. The relationship of the tape and the front operative end portions of the eyes to the inner edge portion of the plate 16 is clearly shown in the drawings. The opposite or rear ends of the fasteners contact with the inner edge of the plate 30 and are guided thereby. In other words, the inner edge of the plate 30 contacts with the rear ends of the fasteners and such contact operates to retain the opposing inner edge of the plate 16 in position between the front operative end portions of the fasteners and the tape.

In the beginning of an operation one end of a tape is inserted into the guiding attachment with the supporting and guiding edges of the plates 16 and 30 in relation to the parts of the tape as indicated in the drawings and as described. Upon placing the tape in engagement with the guiding elements of the attachment the cover strip, in open position as illustrated in Fig. 3, is placed over or above the forward corner portion 37 of the inner edge of the plate 17 by which it is given an initial turn toward closed position and is guided to the rearwardly, inwardly and upwardly inclined edge portion 27 of the guide flange portion 25 and is thereby guided underneath the said flange portion which operates to turn the strip downwardly onto the adjoining edge portion of a fabric 40 which has been placed in position underneath the said flange portion and over the opposed exposed portion of the body portion of the tape and of the plate 30. The corner at the inner edge of the front end of the plate 17 may be turned slightly downwardly as indicated at

40^a in Figs. 1 and 7 of the drawings but the turning down of such corner is not essential to my invention.

To cause the inner edge portion of the tape supporting and guiding plate 16 to enter between the front operative portions 36 of the fasteners and the adjoining main or body portion of the tape 35 I have provided in the bottom portion 15 of the base plate an upwardly projecting protuberance 40^b which is located near the front end of the attachment and intermediate the opposing edges of the plates 16 and 30. The said protuberance may be, though not necessarily, slightly overlapped by the inclined or beveled edge portion 28, previously referred to, of the said plate 16. Preferably the upper side of the inclined or beveled edge portion 28 is beveled as indicated at 40^c for facilitating the entrance of the inner edge portion of the plate 16 near its front end between the ends of the fasteners and the body portion of the tape. As the tape passes through the attachment a portion thereof is elevated by the protuberance as indicated at 40^d. The adjoining edge portion of the tape is held down by the overlying inner edge portion of the tape supporting and guiding plate 16. It will be apparent therefore that the successive elevation of the longitudinal central portion of the tape effects a corresponding elevation of the fasteners as they travel over the protuberance 40^b so that the angular space between the front operative end portion of a fastener and the adjoining part of the body portion of the tape is increased and the entrance of the edge of the plate between the fastener and the tape thereby assured.

For the purpose of properly locating and registering the rear end of the edge portion of the garment as it is fed through the sewing machine with respect to a fastener upon the tape I have provided an elongated opening or slot 41 in the plate 25^a of the attachment through which the front or operative end portions 36 of the fasteners are visible. The tape with the garment having its edge portion interposed between the cover strip 26 in its closed position and the adjoining opposing portion of the main or base part of the tape are fed through the sewing machine by the feed mechanism thereof which is of usual construction and comprises the feed dog 8 and the presser foot 4. The former engages, in the operation as illustrated, with the under side of the main or body part of the tape while the presser foot engages the top side of the tape including the cover strip 26 and with a portion of the fabric of the garment in adjoining relation to the outer overturned edge of the said cover strip.

For the purpose of fastening the attachment adjustably to the top side of the table of the sewing machine I have provided the same with a projection 44 which extends out-

wardly from one edge thereof. Openings are provided partly through the said projection and the main body portion of the attachment. These openings are elongated transversely of 5 the said attachment. Screws 46 extend through the said openings and engage screw threaded openings provided in a detachable plate 47 mounted in a slot or cut out portion formed in the top of the table as indicated at 10 48; or the said screws may engage screw threaded openings provided in the table itself.

It will be seen that by my invention I have provided a tape guiding attachment 15 for guiding the tapes of hook and eye tape garment fastening devices having plates provided with thin or knife-like edges for engaging the tape and the hooks thereon for supporting and guiding the same 20 to the sewing mechanism, and having means whereby the assembling of an edge portion of a garment therewith and in proper relation to parts thereof is facilitated; and it also will be seen that I am enabled to accomplish 25 the results sought to be accomplished by me by the use of a device which while novel yet is extremely simple in construction and operates with great efficiency.

Having thus described my invention, what 30 I claim and desire to secure by Letters Patent is:

1. An attachment of the character described for guiding a tape of hook and eye tape garment fastening means to the sewing 35 mechanism of a sewing machine, which comprises a couple of thin plates supported upon the table of a sewing machine in position to guide a tape to the sewing mechanism of the said machine, the inner edges of the said 40 plates being held in spaced opposed relation to each other, the inner edge of one of the said plates being adapted to engage a tape between portions of the fastening devices carried thereon and the opposing side portion of the said 45 tape, and the edge of the other of said plates being adapted to contact with the ends of the opposite portions of the said fastening devices.

2. An attachment of the character described which is adapted to guide the eye 50 tape of hook and eye garment tape fastening means to the sewing mechanism of a sewing machine, which comprises a base plate, a couple 55 of thin plates mounted on one side of the opposite edge portions of the said base plate, the inner edges of the said second named plates being supported in spaced opposing relation to each other, the inner edge of one of said plates being adapted to engage the 60 said tape between portions of the fastening devices carried thereon and the opposing side portion of the said tape, and the inner edge of the other of said plates being adapted to contact with the ends of the opposite portions 65 of the said fastening devices and operating

to retain the said tape in engagement with the edge portion of the first named plate.

3. An attachment of the character described for guiding the eye tape of garment hook and eye tape fastener means to the sewing mechanism of a sewing machine, which tape comprises a cover strip in initially open position, which attachment comprises a base plate, plates secured upon the opposite edge portions of said base plate, the inner edges of the second named plates being spaced from the said base plate and being located in opposed spaced relation to each other, the inner edge of one of the said plates adapted to engage the tape between the front operative ends of the eyes thereof and the adjoining opposed side portion of the base of the said tape, and the inner edge of the other of said plates adapted to contact with the opposite rear ends of the said eyes, and a plate mounted upon the first of the two second named plates and overlying and being in spaced relation to the inner edge portion thereof, and the said third named plate having an inwardly, upwardly and rearwardly inclined flange portion which is adapted to contact with the open cover strip of the said tape and turn the same from open into closed position.

4. An attachment of the character described for guiding the eye tape of hook and eye tape garment fastening means to the sewing mechanism of a sewing machine, the said tape having an initially open cover strip thereon, the said attachment comprising a base plate, a plate secured to one edge portion of the said base plate and extending inwardly thereover and in spaced relation thereto, a plate secured to the opposite edge portion of the said base plate and extending inwardly thereover and in spaced relation thereto, the inner edges of said plates being located in spaced parallel relation to each other and in substantially the same plane, and a plate mounted upon the upper side of the outer portion of one of the two last named plates and having its inner edge spaced from the plate on which it is mounted, and the said inner edge being provided with an inwardly, upwardly and rearwardly inclined flange portion which is adapted to engage the open cover strip and turn the same over into closed position.

5. An attachment of the character described for guiding the eye tape of hook and eye tape garment fastening means to the sewing mechanism of a sewing machine, the said tape having a cover strip thereon which initially is folded over the operative front ends of the eyes upon the said tape, the said attachment comprising a base plate, a tape supporting and guiding plate mounted upon one edge portion of the said base plate and extending inwardly thereover, the inner edge of said second-named plate being adapted to engage the said tape between the operative

- front ends of the said eyes and the adjoining opposed portion of the tape, a plate mounted upon the opposite edge portion of the said base plate and extending inwardly thereover, its inner edge being located in spaced opposed relation to the edge of the said supporting and guiding plate and being adapted to engage the rear end of the said eyes to retain the tape in engagement with the inner edge of the said supporting and guiding plate, and a plate mounted upon the upper side of the outer portion of the said supporting and guiding plate and having its inner edge portion in spaced relation to the inner edge of the said supporting and guiding plate and also having an inwardly extending flange portion which is adapted to engage the said cover strip and to turn the same over into closed position over the rear end portions of the said eyes and onto the edge portion of a garment which may be located underneath the said flange portion.
5. An attachment of the character described for supporting and guiding a tape of a hook and eye tape garment fastening means to the sewing mechanism of a sewing machine, which attachment comprises a base plate, a tape supporting and guiding plate mounted upon one edge portion of the said base plate and extending inwardly thereof, the inner edge of said plate being spaced from the said base plate, a plate mounted on the opposite edge portion of the said base plate and extending inwardly thereof, its inner edge being located in spaced opposed relation to the inner edge of the said tape supporting and guiding plate, a plate mounted upon the outer portion of the said tape supporting and guiding plate the inner edge of which is located above and in spaced relation to the inner edge of the said tape supporting and guiding plate, and means provided in adjoining relation to the rear end of the said last mentioned plate for enabling a fabric to which the tape is being secured by the sewing mechanism to be placed in predetermined relation to the said tape.
6. An attachment of the character described for supporting and guiding a tape of a hook and eye tape garment fastening means to the sewing mechanism of a sewing machine, which attachment comprises a base plate, a tape supporting and guiding plate mounted upon one edge portion of the said base plate and extending inwardly thereof, the inner edge of said plate being spaced from the said base plate, a plate mounted on the opposite edge portion of the said base plate and extending inwardly thereof, its inner edge being located in spaced opposed relation to the inner edge of the said tape supporting and guiding plate, a plate mounted upon the outer portion of the said tape supporting and guiding plate the inner edge of which is located above and in spaced relation to the inner edge of the said tape supporting and guiding plate, and means provided in adjoining relation to the rear end of the said last mentioned plate for enabling a fabric to which the tape is being secured by the sewing mechanism to be placed in predetermined relation to the said tape.
7. An attachment of the character described for guiding the eye tape of a hook and eye tape garment fastening means to the sewing mechanism of a sewing machine, which eye tape is provided with a cover strip which is initially in open position overlying the front operative ends of the eyes mounted upon the said tape, the said attachment comprising a tape supporting and guiding plate the inner edge of which is adapted to engage the tape between the front operative ends of the eyes thereon and the adjoining opposed portion of the said tape, a plate having its inner edge supported in opposed spaced relation to the inner edge of the tape supporting and guiding plate and adapted to contact with the rear ends of the eyes upon the said tape, and a plate mounted upon the outer portion of the tape supporting and guiding plate the inner edge of which is located above and in spaced relation to the inner edge of the said tape supporting and guiding plate and is provided with an inwardly, upwardly and rearwardly inclined flange portion which is adapted to engage and turn the said cover strip from open into closed position in overlying relation to the edge portion of a garment overlying a portion of the tape, the said last mentioned plate having an opening therethrough in adjoining relation to its rear end through which portions of the eyes upon the said tape are visible whereby one end of the edge portion of the fabric of the garment to which the said tape is to be secured by the sewing mechanism may be positioned in desired relation to any one of the said eyes.
8. An attachment of the character described for supporting and guiding one of the tapes of a hook and eye tape garment fastening means to the sewing mechanism of a sewing machine, which attachment comprises a base plate, a tape supporting and guiding plate mounted upon the said base plate and spaced therefrom, the edge portion of said plate being adapted to engage between the fasteners and the said tape, and means for causing the forward inner edge portion of the said plate to enter successively the spaces between the said fasteners and adjoining portions of the said tape.
9. An attachment of the character described for guiding a tape of a hook and eye tape garment fastening means to the sewing mechanism of a sewing machine, which comprises a base plate, a tape supporting and guiding plate mounted upon the said base plate, the inner edge portion of which tape supporting and guiding plate is spaced from the said base plate, and an upwardly extending protuberance upon the said base plate in adjoining relation to its front end and located laterally of the adjoining inner edge portion of the said tape supporting and guiding plate, the said protuberance being adapted to lift portions of the said tape successively as the latter passes thereover to increase the angle between end portions of the fasteners on the tape and adjoining portions of the tape to facilitate the entry of the inner edge of the front end portion of the said tape supporting and guiding plate between the said fasteners and adjoining portions of the said tape.
10. An attachment of the character described for guiding the eye tape of hook and eye tape garment fastening means to the sewing mechanism of a sewing machine, which comprises a base plate, a tape supporting and guiding plate mounted in spaced relation to the said base plate, the inner edge portion of the said tape supporting and guiding plate consisting of a free edge portion, the front

end portion of the inner edge portion of the said plate being inclined outwardly, the inner edge portion of the said tape supporting and guiding plate adapted to engage between the front operative end portions of the said eyes and adjoining portions of the tape, and means provided upon the said base plate which is adapted to lift the said eyes and cause the said front operative end portions thereof to pass onto the upper side of the inner edge portion of the said tape supporting and guiding plate.

11. An attachment of the character described for guiding a tape of hook and eye tape garment fastening means to the sewing mechanism of a sewing machine, which comprises a base plate, a couple of thin plates supported upon the said base plate, the inner edge portions of which are in spaced relation to each other and the said inner portions constituting free edge portions, one of the said plates adapted to engage between the front operative end portions of the fasteners on the tape, and the inner edge of the other of said plates adapted to contact with the opposite ends of said fasteners, and means provided upon the said base plate for causing the first named plate to enter the spaces between the front operative end portions of the said fasteners and the adjoining portions of the tape.

In testimony that I claim the foregoing as my invention I have hereunto signed my name this 22nd day of January, 1929.
